(57) CLAIM

The ornamental design for a cove light, as shown and described.

DESCRIPTION

FIG. 1 is a front and left side perspective view of the cove light showing our new design;

FIG. 2 is a front elevation view thereof;

FIG. 3 is a rear elevation view thereof;

FIG. 4 is a left side elevation view thereof, the right side being a mirror image thereof;

FIG. 5 is a top plan view thereof; and,

FIG. 6 is a bottom plan view thereof.

The broken lines in the drawings illustrate portions of the cove light and form no part of the claimed design.
